UNITED STATES PATENT OFFICE.

RICHARD ROESLER AND FRANK J. ROESLER, OF CHICAGO, ILLINOIS.

DESIGN FOR A CHRISTMAS-TREE SUPPORT.

58,830.

Specification for Design.

Patented Aug. 30, 1921.

Application filed January 8, 1921. Serial No. 436,001. Term of patent 14 years.

To all whom it may concern:

Be it known that we, RICHARD ROESLER and FRANK J. ROESLER, citizens of the United States, residing at Chicago, in the county of Cook and State of Illinois, have invented a new, original, and ornamental Design for Christmas-Tree Supports, of which the following is the specification, reference being made to the accompanying drawing, forming part thereof.

Figure 1 is a side elevation of a Christmas tree support showing the design; Fig. 2 is a plan view thereof.

We claim:

The ornamental design for a Christmas tree support as shown.

RICHARD ROESLER.
FRANK J. ROESLER.
